EDGE-SETTING MACHINE.

1,178,636.

Specification of Letters Patent. Patented Apr. 11, 1916.

Application filed August 5, 1914. Serial No. 855,117.

To all whom it may concern:

Be it known that I, VINCENZO FRANCHINO, a subject of the King of Italy, and a resident of Orange, in the county of Essex and State of New Jersey, have invented certain Improvements in Edge-Setting Machines, of which the following is a specification.

This invention relates to that class of shoe making machines which are used to round off the lower peripheral edge of the sole of a shoe and has for its objects to provide an improved machine of this character; to admit regulating the machine without stopping the same; to thus adapt the machine to use with a sole of any thickness; to indicate the thickness of sole for which the machine is set; to provide resilient means for pressing the movable sleeve toward the head; to secure simplicity of construction and operation, and to obtain other advantages and results as may be brought out in the following description.

Referring to the accompanying drawings, in which like numerals of reference indicate the same parts throughout the several views, Figure 1 is a front elevation of a machine embodying my invention; Fig. 2 is a longitudinal vertical section of the same; Fig. 3 is a plan view, and Fig. 4 is a cross-sectional view on line A—A of Fig. 2.

In the specific embodiment of the invention illustrated in said drawings, the reference numeral 1 indicates a rotatable spindle preferably mounted horizontally in a suitable base 2. A driving pulley 3 is secured to the spindle as by a set screw 4 and prevents the spindle from shifting longitudinally by engagement with bearing portions 5, 5 of the base, although it will be understood that any suitable or equivalent means could be employed. At one end this spindle is enlarged and forms a head 6 providing an annular shoulder 7 facing toward the opposite end of the spindle. Slidably mounted upon the spindle between said shoulder and the adjacent bearing 5, is a rasping or burnishing sleeve 8 suitably roughened on its end toward the shoulder so as to more readily round off and burnish the edge of the sole when brought into engagement therewith. The rasping or burnishing sleeve 8 is keyed onto the spindle in any suitable manner so as to be slidably but non-rotatably mounted thereon, and to this end are shown a plurality of keys or splines 9 in the central aperture of the sleeve which en-

gage within corresponding slots or keyways 10 cut for convenience in a collar 11 secured to the spindle adjacent the head. Obviously, therefore, the movable sleeve 8 may be slid back and forth upon the spindle at will but will be rotated therewith. It may be here noted that the end of the keys 9 project beyond the end of the sleeve 8 toward the shoulder 7 a distance substantially equal to the smallest thickness of shoe sole to be edged. Furthermore the radially outer face of said keys have the longitudinal edges rounded off and the adjacent outer edges of the slots are also rounded so as to provide a roughened surface for edging the shoe sole. Preferably the metal between the slots is cut away at the periphery of the ring to a suitable depth at a distance from the shoulder 7, this distance when added to the distance the keys 9 project beyond the sleeve 8 being equal to the greatest thickness of sole to be treated.

Preferably between the rasping or burnishing sleeve and the adjacent bearing 5 around the spindle is inserted a helical spring 12 which bears against the sleeve and bearing and tends to normally slide the sleeve toward the shoulder 7. Obviously the sole of a shoe may be inserted at its edge between the shoulder 7 and the sleeve with its bottom facing the sleeve and with the spindle rotating and the spring pressing the sleeve against the sole, frictional wearing and burnishing of the edge will be performed to round off the same as desired. Furthermore the sleeve in shifting to accommodate various thicknesses of sole will press with less force against the thinner, and with greater force against the heavier soles to give a less or greater rounding of the edge.

Under some conditions it is desirable to maintain the sleeve in position to operate upon soles of some particular thickness. With this purpose in view I cut a peripheral groove 13 in the exterior of the rasping or burnishing sleeve and mount thereabove an arm 14 having its lower end forked and riding in said groove. The upper end of said arm is provided with a transverse sleeve 15 slidably supported by a stationary stud 16 fixed above and parallel to the spindle 1 in an extension 17 projecting upwardly from the base. Thus mounted, the arm 14 will slide transversely of itself and parallel to the spindle and will slide the sleeve 8 at the same time. In order to so slide the arm 14,

a screw or threaded member 18 is secured thereto and projects parallel to the spindle through the extension 17 to which the stud 16 is fixed. Said extension is recessed as at 5 19 transverse to the screw and in this recess is held a thumb nut 20 upon the screw. By turning said nut, the screw will be moved longitudinally one way or the other, since the screw is prevented from turning and the 10 nut is prevented from movement longitudinally of the screw by engagement with the walls of its recess 19. In this manner, the rasping or burnishing sleeve 8 may be slid and held in any position desired so as to 15 operate upon any thickness of sole and this adjustment may be made very readily and quickly without stopping the machine or causing any long delays in the operation thereof. Obviously the spring 12 between 20 the sleeve 8 and bearing 5, although advantageous and desirable for positively taking up the lost motion or play always in the same direction, may be omitted if desired when the above described adjusting means 25 are employed.

In order to admit setting the machine readily to the proper thickness of sole, an indicator is provided comprising a swinging hand 21 pivotally mounted in front of a scale plate 22 having appropriate designations 23 of the size for which the machine is set. The lower end of the hand 21 is provided with an arcuate series of teeth 24 in mesh with the teeth of a rack 25 which is fixed 30 with respect to the sleeve 15 and arm 14 whereby movement of the arm in shifting the sleeve will result in a corresponding movement of the rack. Movement of the rack, however, will swing the hand 21 which 35 multiplies the movement in registering upon the scale 23. It is not to be understood, however, that I limit myself to this or any other detail construction except as specifically pointed out in the appended claims 40 when construed in the light of the prior art.

Having thus described the invention what I claim is,—

1. In a machine of the character described, the combination with a rotatable 50 spindle having a shoulder at one end, of a sleeve slidable on said spindle toward and away from said shoulder, said sleeve being non-rotatably mounted on said spindle and having a peripheral groove, a stud parallel 55 to said spindle, an arm in said groove slidably mounted on said stud, a threaded member secured to said arm between the spindle and the stud, and a nut rotatable on said threaded member and arranged by 60 its rotation to slide said sleeve back and forth on said spindle.

2. In a machine of the character described, the combination with a rotatable

spindle having at one end a shoulder, of a rasping or burnishing sleeve slidably mounted 65 on said spindle and having a peripheral groove, a stud parallel to said spindle, an arm slidable on said stud and having an end positioned in said groove, means for moving and holding said arm to move and hold said sleeve in any desired position, and means connected with said arm for indicating the 70 position to which said sleeve is held.

3. In a machine of the character described, the combination with a rotatable 75 spindle having at one end a shoulder, of a rasping or burnishing sleeve slidably mounted on said spindle and having a peripheral groove, a stud parallel to said spindle, an arm 80 slidable on said stud and having an end positioned in said groove, means for moving and holding said arm to move and hold said sleeve in any desired position, said arm having a rack, and a hand having teeth engaging said rack and adapted to be 85 swung thereby as the sleeve is moved for indicating the position of said sleeve.

4. In a machine of the character described, the combination with a base having an extension, of a rotatable spindle journaled in said base, a rasping or burnishing sleeve slidable on said spindle and adapted 90 to be rotated therewith and having a peripheral groove, a stud projecting from said extension parallel to the spindle, an arm 95 slidable on said stud and having an end portion positioned in said groove, means for sliding said arm on said stud and thereby shifting the sleeve to any desired position, a scale plate on said extension, a 100 hand pivoted to swing in front of said scale plate, and means for swinging said hand as the sleeve is slid to any desired position.

5. In a machine of the character described, the combination with a base having a slotted extension, of a rotatable spindle journaled in said base, a rasping or burnishing sleeve slidable on said spindle and adapted to be rotated therewith and having 105 a peripheral groove, a stud projecting from said extension parallel to the spindle, an arm transverse to said stud and spindle and slidable on said stud and having an end portion positioned in said groove, a threaded 110 member secured to said arm and projecting through said extension parallel to said spindle, and a nut on said threaded member 115 within the slot of the extension for moving and holding said threaded member 120 to move and hold said sleeve in any desired position.

VINCENZO FRANCHINO.
